UNITED STATES PATENT OFFICE.

JOHN HOLROYD, OF MANCHESTER, COUNTY OF LANCASTER, ASSIGNOR TO
FRANCIS THYWISSEN AND VICTOR WITTE, BOTH OF LONDON, ENGLAND.

SEWING-MACHINE.

SPECIFICATION forming part of Letters Patent No. 360,095, dated March 29, 1887.

Application filed December 9, 1885. Serial No. 185,184. (No model.) Patented in England May 5, 1885, No. 5,505; in France November 5, 1885, No. 172,084; in Belgium November 13, 1885, No. 70,842; in Germany November 13, 1885, No. 37,095, and in Austria-Hungary January 18, 1886, No. 40,878.

To all whom it may concern:

Be it known that I, JOHN HOLROYD, a subject of the Queen of Great Britain and Ireland, residing at 41 John Dalton Street, Manchester, 5 in the county of Lancaster, Kingdom of Great Britain and Ireland, have invented new and useful Improvements in Sewing - Machines, (which has been patented to me as follows: Great Britain, No. 5,505, May 5, 1885; Bel- 10 gium, No. 70,842, November 13, 1885; and to my assignees Francis Thywissen and Victor Witte as follow: France, No. 172,084, November 5, 1885; Germany, No. 37,095, November 13, 1885, and Austria-Hungary, No. 40,878, 15 January 18, 1886,) of which the following is a specification.

In the accompanying drawings, Figure 1 is a side elevation of so much of a button-hole sewing-machine as is necessary to illustrate 20 the nature of my invention. Fig. 2 is an elevation, with the side cover removed, of the reverse side of the goose-neck or overhanging arm shown in Fig. 1, with its attached parts. Figs. 3, 4, 5, and 6 are detail views hereinafter 25 described.

a is a block, and *b* is a die working in conjunction therewith for cutting the button-hole in the material operated upon, in a manner well understood. The said block *a* is carried 30 by a lever, *c*, hinged or pivoted to the machine at *c'*, so as to be capable of being turned down against the die, or of being thrown back out of the way when not in use.

In order that the block *a* may be securely 35 held in position against the upward pressure of the die during the operation of cutting a button-hole through the material, I employ a spring-catch, *d*, pivoted to the machine at *e*. This spring-catch *d* is provided with a tooth, 40 projection, or hook-like stop, *d'*, adapted to engage with a corresponding tooth, projection, or hook-like stop, *c''*, on the lever *c*, and effectually prevent the said lever and attached block *a* from rising during the cutting opera- 45 tion.

f is a spring secured at one end to the catch *d*, and at its other end to the frame of the ma-

chine, and designed to cause the catch to move forward automatically when the lever *c* is lowered, and to cause the teeth, projections, or stops *d'* and *c''* to become interlocked, as shown. *g* is a handle for moving the spring-catch backward to unlock the said teeth, projections, or stops *d'* and *c''* when it is desired to throw the block *a* and lever *c* backward or upward 55 out of the operator's way.

h is a bent spring, secured at one end to the bearing *i*, in which the lever *c* turns. It is provided at its free end with a projecting portion or detent, *i'*, adapted to enter a recess, *j*, 60 in the end of the lever *c* and retain it automatically in its raised position when thrown back.

When the edges of a button-hole are being bound or sewed one of the divided ends of 65 thread is apt to interfere with the action of the needle or to get on the wrong side thereof, so as to spoil the work. To maintain a clear path for the needle, and also to keep the thread in its proper relative position, there is em- 70 ployed a finger or device pivoted horizontally beneath the base-plate or to the top or face plate of the machine, and worked by a cam on the feed-shaft, so as to oscillate at the proper intervals and carry the end of the thread clear 75 of the needle and to the proper side thereof.

Fig. 3 is an under side view of the top or face plate of the machine with a finger or device for the purpose stated pivoted thereto. Fig. 4 is a side elevation of the said plate in 80 its working position, with the finger or device, feed-shaft, cam, and attached rotating hook.

k is the finger, pivoted at *k'* and provided with a downwardly-projecting pin, *k''*, so arranged relatively to a cam, *l*, on the feed-shaft 85 *m* as to be moved thereby in one direction at the proper intervals, movement in the opposite direction being effected by a spring, *n*. *o* is the hook or looper.

An improved pull-off device and tension 90 arrangement are also provided, which are shown in Fig. 2, and in Figs. 5 and 6, which are transverse sections on the lines *x x* and *y y*, respectively, of Fig. 2. In the pull-off de-

vice there is employed a finger or lever, *p*, situated between two standards or guides, *q*, across which the thread passes from the bobbin *r*, Fig. 1. This finger is worked or oscillated by a cam, *s*, on the upper shaft, *t*, of the machine, so as to pull a certain length of thread from the bobbin at each stroke of the needle.

u is a double tension-disk, which is caused by another cam, *u'*, on the shaft *t* to nip or hold the thread that passes between the two portions or disks thereof when the finger *p* moves to the right, as shown in dotted lines in Fig. 5. To this end the double tension-disk is carried by a pin, *u''*, which is moved to the right by a bar or lever, *v*, actuated by the cam *u'*, whereby the two halves of the tension-disk are forced against the frame of the machine, and the thread between them nipped or held fast.

The hereinbefore-described tension arrangement is applicable to sewing-machines other than those of the button-hole type.

What I claim is—

1. The combination, with a block-carrying lever pivoted above the base-plate and having a notch in its under side, of a catch-lever pivoted at its lower end beneath the base-plate, its upper end extending above said plate and having a hooked projection for taking into the notch in the block-lever, and a coiled spring, the ends of which are attached to the lower end of the catch-lever and to the frame of the machine, substantially as described, and for the purpose set forth.

2. The combination, with a pivoted block-

carrying lever having a notch in its pivoted end, of a bent spring, one end of which is secured to the bearing for the lever, the other end being provided with a detent for engaging with said notch when the lever is in an elevated position, substantially as described, and for the purpose set forth.

3. In a button-hole sewing-machine, mechanism for carrying one of the ends of the thread clear of the needle, said mechanism consisting of a finger, as *k*, pivoted to the face-plate and having a downwardly-projecting pin, as *k'*, a cam, as *l*, on the feed-shaft, with which pin *k'* engages to throw the finger, and a spring, as *n*, for returning the finger to its normal position, combined substantially as described.

4. In a sewing-machine, the combination, with a pull-off, of a tension device consisting of a horizontally-movable rod mounted in a standard on the goose-neck, the said rod carrying at one end a double disk for nipping the thread, a lever, the upper end of which engages with the other end of the disk-rod, and the lower end of which is pivoted in the goose-neck, a cam on the upper shaft of the machine for contacting with the lever and reciprocating the disk-shaft, and a spring for pressing the lever against the cam, substantially as above set forth.

JOHN HOLROYD.
